UNITED STATES PATENT OFFICE.

DAVID P. MOORE AND SAMUEL B. PACK, OF WASHINGTON, DISTRICT OF COLUMBIA,
ASSIGNORS, BY DIRECT AND MESNE ASSIGNMENTS, TO PACKMORE MANUFACTUR-
ING COMPANY, A CORPORATION OF DELAWARE.

SUCTION CLEANING-MACHINE.

1,237,675.

Specification of Letters Patent. Patented Aug. 21, 1917.

Application filed January 29, 1910, Serial No. 540,795. Renewed January 18, 1917. Serial No. 143,196.

To all whom it may concern:

Be it known that we, DAVID P. MOORE and SAMUEL B. PACK, citizens of the United States, residing at Washington, in the District of Columbia, have invented certain new and useful Improvements in Suction Cleaning-Machines, of which the following is a specification, reference being had therein to the accompanying drawing.

Our present invention relates to improvements in suction cleaning machines, the main object of the machine being to mount the casing, which carries the suction head and suction creating device, so that it will glide freely over the surface to be cleaned and rest thereon of its own weight, a handle being pivoted to the casing and operably connected to the suction creating device, so that when the machine is pushed or pulled, that is, reciprocated back and forth by the operator, the handle will be raised and lowered, thus operating the suction creating device and guiding the machine, the action of the suction creating device drawing the air, dust laden, through the suction head, which is in operative relation with the surface traversed by the machine.

To clearly understand our invention, so as to readily appreciate the various advantages a machine constructed accordingly will have, reference must be had to the accompanying drawings, in which:—

Figure 1 is a side elevation of a machine embodying our invention with a portion of the casing removed to show the pump.

Fig. 2 is a top plan view.

Fig. 3 is a side elevation of a modified form.

Fig. 4 is a side elevation of another modified form employing a bellows pump.

Fig. 5 is a side elevation of another modified form with the rear portion of the casing removed to show one of the bellows pumps, and

Fig. 6 is a top plan view thereof.

Fig. 7 is a sectional view taken on the line VII—VII of Fig. 6.

Referring to the drawings:

The numeral 1 designates a dust collecting and air filtering casing, having the casters or wheels 2, and having mounted for operable relation therewith the suction head support 3, and self-adjusting suction head 4, which is of the type set forth in our ap-

plication filed January 27th, 1910, Serial No. 540,391, whereby the mouth thereof is always upon the surface traversed by the machine, and rests so lightly and freely as to not retard the machine. The casing is provided with the clean-out door 5, and the rear extension 6, in or upon which is seated the double-acting diaphragm suction pump 7, which is in communication with the casing through the medium of the two valved inlet pipes 8. This pump is covered by the casing or dome 9, and has its piston or diaphragm operating rod 10, passing upwardly through the casing, with its upper end secured pivotally to the cross-bar 11, of the substantially U-shaped or bailed handle 12, which is pivotally secured to the lugs 13, or in any practical manner to the casing, or part of the machine, whereby the pushing or pulling action upon the handle as the machine is reciprocated, or moved back and forth will cause the machine to glide over the surface to be cleaned, and simultaneously cause the handle to rise and fall and operate the pump. The extension 6, is mounted upon casters 2', and may be weighted if necessary, to prevent the rear end of the machine from being lifted from the floor, as the handle is pulled upwardly.

In Figs. 3 and 4, we deviate slightly from the construction above described, mounting the dust collecting and air-filtering casing 14, upon the casters 15, and mounting the diaphragm double acting pump 16, Fig. 3, or the double acting bellows pump 17, Fig. 4, upon and supported by said casing. The casing in these instances is provided with the suction head 4' and support 3'. A handle 18, similar to the handle 12 is employed, the lever 19, connected to the pump piston rod 20, Fig. 3, being fulcrumed upon the standard 21, having its reduced end 22, slidably mounted in the guide 23, of the handle, whereby the movement of the handle will operate the pump. In Fig. 4, the movable member 24, of the bellows pump has a lever 25, connected slidably to the handle, the principle of operation being identical with that of Fig. 3.

In Figs. 5 and 6, we employ the same dust collecting casing, suction head and pump support as shown in Figs. 1 and 2, the only difference being that we employ two bellows pumps 25', which are connected to the casing

to draw air through the pipes 26, their movable members 27, each being provided with a link or rod 28, which operably connects each bellows to its member 12', of the U-shaped bail handle.

From the foregoing description, it is evident that any and all forms herein shown and described are provided with a pivoted operating and guiding handle, which is 10 adapted to move in a vertically reciprocatory direction to operate the suction creating devices, as the machine is reciprocatingly pushed and pulled over the surface to be cleaned, thus making said handle accomplish the double function of propelling or 15 guiding the machine and operating the pump.

What we claim, as new, is:—

1. A portable suction cleaning machine, 20 having a body mounted upon wheels, a suction nozzle carried by the body and disposed to engage the surface traversed, a suction creating device carried by the body, and a vertically swinging handle pivoted to the body for propelling the machine back and forth, said handle being operably connected to the suction creating device, whereby the rise and fall of the handle during the back and forth movement of the machine actuates the suction creating device while the machine is in motion.
2. A portable suction cleaning machine, 25 having a dust receptacle, a suction creating device, a suction nozzle disposed to engage the surface traversed, and a vertically swinging handle for propelling the machine operably connected to the suction creating device, whereby the rise and fall of the handle during the alternate back and forth move-

ments imparted to the machine by the handle 40 will simultaneously operate the suction creating device.

3. In a portable suction cleaning machine adapted to be operated by an alternate back and forth movement over the surface, the 45 combination of a suction creating device, a dust receptacle, a nozzle operably carried by the machine in its path of travel, and a rearwardly extending vertically swinging handle for propelling the machine and operating the suction creating device, the said handle being operably connected to the suction creating device and mounted to permit of a movement from the surface when the machine is pulled backwardly and a movement toward the surface when the machine is pushed forwardly.

4. In a portable suction cleaning machine, the combination of a suction creating device, a handle operably connected to the suction 60 creating device, the said handle being pivoted to and extending rearwardly of the machine to permit the machine to be propelled over the surface thereby, and mounted to permit of a movement from the surface when 65 the machine is pulled backwardly and a movement toward the surface when the machine is pushed forwardly, and a suction nozzle yieldingly connected to and carried by the machine.

In testimony whereof we affix our signatures in presence of two witnesses.

DAVID P. MOORE.
SAMUEL B. PACK.
